UNITED STATES PATENT OFFICE

KARL DAVIS ROBINSON, OF NEW YORK, N. Y., ASSIGNOR TO BARRETT & COMPANY, A CORPORATION OF NEW JERSEY

DESIGN FOR LEATHER OR SIMILAR ARTICLE

Application filed July 9, 1931. Serial No. 40,477. Term of patent 14 years.

To all whom it may concern:

Be it known that I, KARL DAVIS ROBINSON, a citizen of the United States, residing in the city and State of New York, have invented a new, original, and ornamental Design for Leather or Similar Article, of which the following is a specification, reference being had to the accompanying drawing, forming part thereof.

In the drawing:—

The figure is a plan view of a piece of leather showing my new design contained within the upper left-hand rectangle outlined on the figure by the dot and dash lines. This unit may be repeated over the surface of the article in the relation indicated by the extensions of the figure beyond the said rectangle.

I claim:

The ornamental design for leather or similar article, substantially as shown and described.

KARL DAVIS ROBINSON.
